UNITED STATES PATENT OFFICE.

ERNEST M. WHITE, OF PHILADELPHIA, PENNSYLVANIA.

SHOE CHANNELING AND GROOVING MACHINE.

SPECIFICATION forming part of Letters Patent No. 577,544, dated February 23, 1897.

Application filed December 4, 1895. Renewed September 30, 1896. Serial No. 607,498. (No model.)

To all whom it may concern:

Be it known that I, ERNEST M. WHITE, a citizen of the United States, residing in Philadelphia, Pennsylvania, have invented certain 5 Improvements in Shoe Channeling and Grooving Machines, of which the following is a specification.

The object of my invention is to construct a shoe channeling and grooving machine in 10 such a manner that a former can be used similar to that used on a rounding machine, thus making it unnecessary to provide special formers for the channeling and grooving machine.

15 A further object of the invention is to so mount the tool that it can be positively adjusted toward and from the former, as fully described hereinafter.

In the accompanying drawings, Figure 1 is 20 a view of sufficient of a channeling and grooving machine to illustrate my improvements. Fig. 2 is a side view. Fig. 3 is a detached view of the former. Fig. 4 is a detached view of the cam-plate. Fig. 5 is a diagram 25 view showing the slide resting against the former.

A is a standard on which in the present instance is a fixed cam A', having a cam-groove a, in which the rollers or projections b of the 30 carriage B travel.

C is a table on which is mounted the carriage B, and this table is driven from the main shaft of the machine through a bevel-pinion c and bevel-wheel c', Fig. 2, so that 35 when power is applied the carriage B will travel around the cam A', it being connected to the table C by a connecting-rod c'.

40 Mounted on standards a' is a detachable former A², having openings a² for the reception of the reduced portions of the standards a' and holes a³ for the reception of pins e of the cam-plate E, which is mounted between the former A² and the rear standard a', so that when the former is in position the 45 cam-plate will have fixed relation to it, and in such a manner that the tool will be drawn away from the former in passing around the heel portion, as in this machine the sole is not channelled at the heel.

50 Both the former A² and cam-plate E are detachable and reversible, so that the same parts can be used to channel the rights and

lefts of the shoe-sole by simply reversing the former, and when a cam-plate is of a peculiar form this can be also reversed. This plate 55 can be used with formers of different sizes and shapes.

A³ is a clamp adapted to secure the sole x to the former A², and this clamp can be fastened in any suitable manner. The sole x 60 before being channelled is preferably rounded or cut to shape, and as in most cases the former for the rounding-machine will be the same as the former for the channeller it will fit accurately on the former, and in order to enable 65 the operator to mount it properly I provide two pins e on the cam-plate E, which extend above the former, as shown in Fig. 2, to act as stops and guides for the heel portion of the sole-blank, so that all that is necessary is 70 simply to place the sole-blank on the former, force it against these pins, and adjust the toe, and then secure it in position by the clamp. The clamp is considerably smaller than the sole-blank, so as to allow the channeling-tool 75 to pass around the sole.

It will be understood that the pins e, as well as the pins e' on the cam-plate E, extend on both sides of the plate, so that the plate can be reversed, although in some instances 80 the pins may be only on one side where it is not required to reverse the plate.

Mounted on the carriage B is a plate B'. Pivoted to this plate at i is a carrier I, on which is a slide I', adjustable longitudinally 85 on the carrier by the screw i'. On the face of this carrier are two projections i², which bear against the former A² when the channeller is cutting.

On the slide I' is a transversely-adjustable 90 slide I², to which is pivoted at i³ the tool-head I³, carrying the channeling-tool f'. Adapted to slide vertically on this tool-head is a presser-foot f², which rests upon the sole-blank in advance of the channeling-tool. The cutting 95 tools are adjustable vertically in respect to the sole by means of the set-screw i⁴, and are held to the work by means of the spring i⁵.

I preferably arrange the pivot i directly under the cutting edge of the grooving-tool 100 and extend the plate B', so that it will project under the former A² when the tool is cutting. Thus the tool-carriage is held rigidly in respect to the former. At the same time

- the carrier I is free to move laterally on this pivot, so that the two bearing-points γ^2 on the slide I' will always be in contact with the former, and as the tendency of the spring in the carriage B is to force the plate and its carrier against the former the cutting-head will be rigidly supported at all times, even in passing around a pointed toe or the corners of a square toe.
10. A proper channel cannot be made around the toe of a pointed sole or around the corners of a square sole by the ordinary machines now in use; but by my machine the proper channel can be made, as the tool is held rigidly, no matter what portion of the sole is being channeled.

I preferably notch the outer end of the carrier I so as to receive the plate E, as shown in Fig. 2, although in some instances the bearing-point γ^2 may extend sufficiently below the former to come in contact with the cam-plate E.

It will be understood that my invention can be applied to a machine in which the tool-carriage is stationary and the former travels around a given center in respect to the tool.

I claim as my invention—

1. The combination of the former, means for clamping a sole-blank thereon, a cam-plate mounted under the former and extending beyond the heel portion thereof, the tool-carrier, tools thereon, said former being detachable, substantially as described.
2. The combination of a detachable former, a cam-plate mounted under the former and extending beyond the heel portion thereof, means for alining the former and cam-plate, pins on the cam-plate extending above the surface of the former at the heel and acting as stops for the sole-blank, a carrier and tools thereon, substantially as described.

3. The combination of a detachable former, a detachable cam-plate mounted under the former and extending beyond the heel portion thereof, means for alining the former and cam-plate, pins on each side of the cam-plate, the upper pins extending above the surface of the former at the heel and acting as stops for

the sole-blank, a carrier and tools thereon, substantially as described.

4. The combination of the former, a clamp adapted to secure the sole-blank to the former, a carriage, a plate mounted on said carriage and having an extension passing under the former during the cutting operation, a carrier pivoted to said extension, a slide mounted on said carrier and adjustable toward and from the former, said slide having two bearing-points adapted to rest against the former, and cutting-tools carried thereby, substantially as described.

5. The combination of the former, means for clamping the sole thereon, a tool-carriage, a plate pivoted to said carriage and extending under the former when the tool is cutting, a carrier pivoted to the extension of the plate, a slide mounted on said carrier and adapted to rest against the former, an adjusting-screw for adjusting the slide longitudinally on the carrier, tools carried by said slide, substantially as described.

6. The combination in a shoe channeling and grooving machine, of the table, means for rotating the same, a fixed cam, a fixed former above the cam, a cam-plate mounted under the former, a clamp for securing the sole-blank to the former, a carriage adapted to the camways in the fixed cam, a plate on the carriage, a pivoted carrier pivoted to the extended portion of the plate, said pivoted carrier passing under the former during the cutting of the blank, a longitudinally-adjustable slide mounted on the carrier having two bearing-points resting against the former when the tools are cutting, a transversely-adjustable slide mounted on the longitudinally-adjustable slide, a tool-head pivoted to the said slide, channeling and grooving cutters and a presser-foot, substantially as described.

In testimony whereof I have signed my name to this specification in the presence of two subscribing witnesses.

ERNEST M. WHITE.
